APPARATUS FOR THE TREATMENT OF
ARTIFICIAL MATERIALSRaymond D. Reel, Keyser, W. Va., assignor to
Celanese Corporation of America, a corpora-
tion of Delaware

Application July 29, 1942, Serial No. 452,749

6 Claims. (Cl. 28—59.5)

This invention relates to improvements in the stretching of filamentary materials, and relates more particularly to improved apparatus for stretching filaments, yarns and threads herein-after referred to as "threads," while they are travelling and while they are under the influence of a softening medium, in order to enhance the textile properties thereof such as, for example, to improve the tensile strength. The apparatus of the present invention is particularly applicable to the production of threads, having a basis of cellulose acetate, or other cellulose ester or ethers, or other synthetic material, of high tensile strength.

In stretching devices heretofore employed, the application of the softening medium was performed in one large chamber on a considerable number of ends of threads of thermoplastic filaments. At the beginning of the operation the ends were drawn from the source of supply, formed into a warp, drawn through a multi-end stretching chamber and the individual ends then packaged separately. After the operation was started, if an end or several ends broke there was no way of tying them in, thus producing considerable waste. Another source of waste, in the operation of prior methods, was the long length of thread necessary to be passed through the device in starting up. On the application of the softening medium, after threading up, softening of the material took place gradually and the threads were fed into the apparatus at a continuously decreasing speed. It was necessary that the thread be kept moving, since otherwise it would not withstand the continued action of the softening medium and breakage would result. As the speed of the input of the threads was decreased gradually with the application of softening agent considerable skill was necessary to prevent broken ends. Furthermore, due to manual manipulation and the high rate of input of thread, longer lengths than necessary of insufficiently stretched yarn were produced in starting up the prior devices. It is accordingly an object of this invention to provide an improved device for stretching threads which will be free from the above-mentioned and other disadvantages and which will be especially simple in construction and efficient in operation.

An important object of this invention is the provision of a novel and efficient device for stretching a single end of thread wherein said single end is passed through a small tube having two interconnected chambers into one of which is fed a medium for softening said thread.

Another object of this invention is the provision of a thread stretching device having means for softening the thread and wherein the rolls by which the rate of input or feed to the thread softening means is determined are located outside of said thread softening means.

A further object of this invention is the provision of a thread stretching device having thread softening means comprising two interconnecting chambers in one of which is contained water and in the other a thread softening medium, the water being maintained at 5 or more pounds of higher gauge pressure than the pressure in the chamber containing the softening means.

15 Another object of this invention is the provision of a thread stretching device having automatic tension control on the thread taking-up means, thus making for more accurate control of stretch and lowering the requirements of operative skill necessary to operate the device efficiently.

20 Still another object of this invention is to provide a thread stretching device which produces stretched thread at a much greater speed than heretofore possible.

25 Other objects of this invention, together with certain details of construction and combinations of parts, will appear from the following detailed description and drawings.

In the drawings where there is shown one embodiment of my invention,

30 Figure 1 is a side view, partially in cross-section and more or less diagrammatic, of the improved device of my invention,

35 Figure 2 is an enlarged top plan view of the takeup feed roll and automatic guides cooperating therewith in the position of starting up the device,

40 Figure 3 is an enlarged view similar to Figure 2 with the automatic guides in operative position to effect the maximum stretching or taking-up effect on the yarn, and

45 Figure 4 is a detail view of the guide arm pivot and tension member.

Like reference numerals refer to like parts throughout the several views of the drawings.

According to the present invention, in the operation for stretching material in the form of filaments or single ends of thread by applying tension to said material while it is travelling and under influence of a softening medium, the degree of stretch effected is changed, for starting the operation or terminating it, by placing the ratio of the length of thread fed to the length of thread drawn from the device under the control of the tension in the material as the material becomes softened. By employing this invention the

degree of stretching of each end of thread is made a function of the increasing softness of that particular end of thread as the supply of softening medium is turned on at the starting up of the operation, so that the degree of stretch is made to follow automatically the softening of the yarn in a smooth and economic manner. In a similar manner, as the supply of softening medium is cut off at the end of the operation or for any other reason, the degree of stretch is automatically reduced preventing waste resulting from broken ends. In the device of my invention it is also desirable to reduce overall tension other than that supplied by the feed rolls and the stretching roll. This I accomplish by providing at the intake end of the pressure treating chamber a fluid pressure chamber in which the pressure exceeds that in the treating chamber, thus creating a flow of liquid through the thread entrance orifice into the treating chamber so that the travelling thread is positively carried thereto. For the purpose of controlling the degree of stretch by tension-sensitive means my device is provided with conical stretching roller with movable guides responsive to the tension on the thread for governing the path of the thread with respect to the roller as will hereinafter be described more fully.

Referring now to the drawings wherein one embodiment of my invention is shown, the reference numeral 1 indicates a single end of thread drawn from a bobbin 2 and passes through a pigtail guide 2' into a trough 3 containing a liquid 3' for washing out or removing any undesired substances on or in the thread, such as, for example, residual solvent. While the source of supply is here shown as a bobbin, it is to be understood that any other thread package may be employed, or the thread may come directly from the metier. Rollers 4 are provided to guide the thread 1 below the surface of the liquid 3' in trough 3. Mounted on or above trough 3 is a drying frame generally indicated by reference numeral 5, which drying frame comprises suitable uprights or supports 6 on which are rotatably mounted guide rollers 7 over which the thread 1 is caused to travel through a circuitous path of a length sufficient to dry the thread or to serve as an air path for assisting to remove residual solvent. The thread 1 passes from frame 5 over guide roller 8 and may be led into a trough 9 containing water or other conditioning liquid 11, trough 9 being provided with rollers 12 for guiding the thread beneath the surface of the liquid therein. The water is used to remove or counteract the effect of residual solvent in the supply yarn, to prevent counter-flow of softening medium into the water chamber, to inject yarn passing through the water chamber into the other chamber and to provide moisture in said other chamber.

The thread 1 leaves the trough 9 over a guide roller 12' and passes through a pigtail guide 13 and then between rollers 14 and 15, either or both of which may be positively driven, which rollers are adapted to feed the thread to a thread treating device, generally indicated by reference numeral 16, where the thread is subjected to a softening medium.

The treating device 16 shown in Figure 1 employs steam to soften the thread. For the above purpose the device 16 is provided with a steam chamber 17 having means 18, such as a pipe which may have a control valve (not shown)

thereon, for admitting the steam thereto. A drain 19 may be provided for withdrawing condensate and fluid entering from the adjoining auxiliary chamber 21. Chamber 21 is positioned 5 at the entrance end of the steam chamber 17. Water or other fluid is introduced into this chamber by a pipe 22 and withdrawn by a pipe 23. The pressure in the chamber 21 is maintained at substantially that of or higher than that of the 10 steam in the chamber 17 so that there is a flow of liquid through the orifice 24. This serves to inject or assist in carrying the travelling thread through the orifice 24 into the chamber 17. An orifice 25 is provided at the entrance end of the 15 fluid chamber 21 and an orifice 26 at the exit end of the steam chamber 17 for the passage of the thread through the treating device, the orifices all being of small dimension to maintain the pressures in chambers 17 and 21.

20 A stationary guide 27 is provided to direct the thread 1 coming from the steam chamber 17 on to a stretching or taking-up device shown at 28 in Figure 1 and in greater detail in Figures 2, 3 and 4. Guides 29 and 30 are provided to direct 25 the stretched thread by means of a ring 31 and ring rail 32 on to a rotating bobbin 33. However, any other suitable packaging means, such as cap twisters, Topham boxes, etc., may be employed.

30 The means for the automatic handling or drawing the thread under uniform tension and feeding it to the take-up or packaging device at lineal rates varying from zero to the maximum capacity of the device is shown in detail in Figures 2, 3 and 4. This means comprises a conical roll 34 mounted on a shaft 35 that is positively driven in timed relation to the feed rollers 14 and 15. An auxiliary collar 36 is provided on the smaller end of the roll 34 to prevent thread from 40 running off the roll on to the shaft 35 and bearings thereof (not shown). The conical roll 34 is provided with a cylindrical portion 37 adjacent to the base thereof.

45 Means are provided for directing the thread 1 on to conical roll 34, said means comprising a pair of guides which are movable in response to the tension on the thread. To this end there is provided a bracket 38 having an arm 41 on which is pivoted at 42 a guide supporting arm 43 mounted on an ear 44 of the arm 41 is a member 45 bent to form guides 46 and 47. To the arm 43, at the opposite end from the member 45, is attached a contractile spring 48 having a connecting link 49 which passes through a stop 51 mounted on a bracket 52. The connecting link 49 is threaded as indicated at 53 and is provided with a thumb screw 54 that abuts against the stop 51 so that the tension on the spring 48 may be adjusted.

55 A front guide 55 is formed on one end of a rod 56 that is carried on a pivot 57 journaled in a bracket 58. The rod 56 extends beyond the pivot to rest against the arm 43 to effect a unified or correlated movement of the front and rear guides. A spring 59 is attached to the rod 56 and to the bracket 58 for the purpose of holding the rod 56 against the arm 43 regardless of the position of said arm.

60 In operation the thread 1 is passed through the liquids 3' and 11 (which may be eliminated in some processes), on to the feed rolls 14 and 15, through the treating device 16, through the stationary guide 27 and pivoting back guide 46, thence over and approximately half way around 75

conical roll 34 to the movable front guide 55, from which it is passed down around said roll 34 and up through back guide 47 which is integral with back guide 46, thence again over the roll 34 to the stationary guide 29 and to the packaging device.

After the thread is arranged as described above, the feed rolls 14 and 15 are driven at a constant speed equal to or lower than the peripheral speed of the smallest part of the roll 34 and the application of the softening medium is started in the chamber 17. As the thread at the starting point has little stretch the tension of the yarn pulls the pivoted arm 43 to the narrow end of the cone so that the output is substantially that of the input. As the softening medium begins to soften the thread, the thread begins to stretch allowing the tension of the spring 48 on the pivoted arm 43 to swing the arm toward a larger part of the conical roll 34. The front guide 55 follows the rear guides 46 and 47, carried on the arm 34, toward the larger part of the conical roll due to the tension of the spring 59 holding the rod 56 against the arm 34. When the full effect of the softening medium is imposed upon the yarn its softness or stretch will permit the arm 43 to so move that from then on the path of the thread will be around the cylindrical section 31 of the roll 34. The ratio of the diameter of the section 31, or output, to the diameter of the rolls 14 and 15, or input, will be the degree of stretch imparted to the yarn. In shutting off the softening medium the reverse operation takes place. It is obvious, therefore, that the yarn is stretched as soon and as much as the effect of the softening medium will allow and yet at no time is there applied a stretching or taking-up tension which would break the yarn.

This invention is applicable to the stretching of thermoplastic threads or threads capable of being softened by solvent vapors and/or liquids such as those made of or containing derivatives of cellulose. Examples of derivatives of cellulose are the organic acid esters of cellulose such as cellulose acetate, cellulose formate, cellulose butyrate, cellulose propionate and cellulose acetate-propionate; the cellulose ethers such as ethyl cellulose, methyl cellulose and benzyl cellulose; the partial or completely saponified esters of cellulose; regenerated or reconstituted cellulose; and the linear polymers of high molecular weight such as the linear condensation product of a polyamide, condensation products of dicarboxylic compounds with diamine compounds and condensation products of diketenes with compounds containing two reactive hydrogens as diamines, glycols, etc. The threads may be monofil or a plurality of filaments grouped together either with or without twist to form a thread.

It is to be understood that the foregoing detailed description is given merely by way of illustration and that many variations may be made therein without departing from the spirit of my invention.

Having described my invention, what I desire to secure by Letters Patent is:

1. In an apparatus for stretching a single end of thread the combination with a chamber for the application of a softening medium to a travelling thread, means for feeding the thread at a constant speed into said chamber and means for drawing the thread out of said chamber, of means including a plurality of separate, co-operating guides on opposite sides of said drawing means responsive to the degree of softness

of the thread for engaging the thread and to direct its path on said drawing means for changing the speed of the thread drawn from said chamber.

5 2. In an apparatus for stretching a single end of thread, the combination with a chamber for the application of a softening medium to a travelling thread, means for feeding the thread at a constant speed into said chamber and means for drawing the thread out of said chamber including a roll having a conical surface, of means including guides on opposite sides of said roll responsive to the degree of softness of the thread for engaging the thread and for directing its path on said roll for changing the speed of the thread drawn from said chamber.

10 3. In an apparatus for stretching a single end of thread, the combination with a chamber for the application of a softening medium to a travelling thread, means for positively feeding the thread into said chamber and means for positively drawing the thread out of said chamber including a roll having a conical surface, said roll being driven at a uniform speed and in timed relation to the speed of said feeding means, of means including a pivoted guide at one side of said roll and a pivoted guide at the opposite side of said roll responsive to the degree of softness of the thread for engaging the thread and directing its path on said drawing means for changing the speed of the thread drawn from said chamber.

15 4. In an apparatus for stretching a single end of thread, the combination with a chamber for the application of a softening medium to a travelling thread, means for positively feeding the thread into said chamber and means for positively drawing the thread out of said chamber including a roll having a conical surface, said roll being driven at a uniform speed and in timed relation to the speed of said feeding means, of means including a pivoted arm, a back guide carried by said arm, a pivoted rod, a front guide on said rod, an extension on said rod for engaging said pivoted arm to effect correlated movement of said back guide and front guide whereby the said means is responsive to the degree of softness of the thread for engaging the thread and directing its path on said drawing means for changing the speed of the thread drawn from said chamber.

20 5. In an apparatus for stretching a single end of thread, the combination with a chamber for the application of a softening medium to a travelling thread, means for positively feeding the thread into said chamber and means for positively drawing the thread out of said chamber including a roll having a conical surface, said roll being driven at a uniform speed and in timed relation to the speed of said feeding means, of means including a pivoted arm, an adjustable tension urging said arm to swing toward the larger end of said roll, a back guide carried by said arm, a pivoted rod, a front guide on said rod, and an extension on said rod for engaging said pivoted arm to effect correlated movement of said back guide and front guide whereby the said means is responsive to the degree of softness of the thread for engaging the thread and directing its path on said drawing means for changing the speed of the thread drawn from said chamber.

25 6. In an apparatus for stretching a single end of thread, the combination with a chamber for the application of a softening medium to a travelling

elling thread, means for positively feeding the thread into said chamber and means for positively drawing the thread out of said chamber including a roll having a conical surface, said roll being driven at a uniform speed and in timed relation to the speed of said feeding means, of means including a pivoted arm, a spring urging said arm to swing against the tension of the thread toward the larger end of said roll, a back guide carried by said arm, a pivoted rod, a front

guide carried by said rod, an extension on said rod to hold it in engagement with said arm to effect correlated movement of said back guide and front guide whereby the said means is responsive to the degree of softness of the thread for engaging the thread and directing its path on said drawing means for changing the speed of the thread drawn from said chamber.

RAYMOND D. REEL.
